UNITED STATES PATENT OFFICE.

ARTEMAS S. KIMBALL, OF BELLOW'S FALLS, VERMONT, ASSIGNOR OF ONE-HALF HIS RIGHT TO SAMUEL S. ORDWAY, OF SAME PLACE.

IMPROVEMENT IN SLATE ROOFS.

Specification forming part of Letters Patent No. **150,056**, dated April 21, 1874; application filed December 31, 1873.

To all whom it may concern:

Be it known that I, ARTEMAS S. KIMBALL, of Bellows Falls, Vermont, have invented an Improvement in Slate Roofs, of which the following is a specification:

The object of my invention is to lay slates upon the roofs of buildings in such a manner as to make them actually fire-proof. This I accomplish by means of an iron frame-work, to which the slates are attached, elevating them above the wood, and thereby giving space for dead air.

S is an iron standard with an angular slot in the top of it, formed to be set into the rafters to support the bars upon which the slates are fixed. B is an iron bar with hooks in its upper edge to hold the slates and tenons on the ends to fit the slots in the standards. These hooks on the edge of the bar are at such a distance apart as the width of the slate may require, so that if the slates are one foot wide there will be two oblong holes punched two inches from the end of the slate, and three

inches from the sides or edges of the slate, leaving the two holes in the slate just six inches apart. The hooks on the bars will be placed the same distance apart as the holes are in the slates, except at the beginning of each alternate row, when a half-slate will be used, in order to break joints. Two hooks on the end of each alternate bar, nearer together, will be made to hold the half-slate. The slates when put on will slip down under the hooks and be held securely. The standards and bars are so constructed as to obtain the lightest weight compatible with the strength required.

I claim as my invention—

The iron frame-work upon which the slates are elevated above the wood, and to which the slates are fastened by means of hooks on the bars, substantially as described.

ARTEMAS S. KIMBALL.
